UNITED STATES PATENT OFFICE.

JAMES C. ANDERSON, OF PHOENIX, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed October 7, 1921. Serial No. 505,983.

To all whom it may concern:

Be it known that I, JAMES C. ANDERSON, a citizen of the United States, residing in Phoenix, in the county of Oswego and State 5 of New York, have invented certain new and useful Improvements in Typewriting Machines, of which the following is a specification.

This invention relates to work-positioning 10 devices for typewriting machines.

The main object of the invention is to provide improved means for guiding a short sheet or card to the platen and to facilitate rapid positioning of the sheet to a plurality 15 of line-space positions. Other objects are to provide simple and effective means for this purpose economical to manufacture and readily applicable to machines in use.

In carrying out the invention, an aligning 20 table with upstanding side members at the proper distance apart to receive the work-sheet or card is mounted above the platen. The upstanding members or sides are also provided with ledges or flanges overhanging 25 the table so as to tend to prevent movement of the sheet away from the table, and one of the members is also supplied with a resilient arm or finger extending across the platen at the printing line so as to hold the card or 30 sheet in position against the platen. Obviously, two resilient arms may be provided, one for each side member. Preferably, however, only one is used so as to enable typing to be effected close to the other edge of the 35 sheet. The table may also be provided with upper edge-gaging means at its upper edge.

As herein disclosed, the invention is illustrated as adapted for use in filling out a card 40 on which two lines of entries are to be made. The card may be placed in position on the table in different ways but preferably by bending or bulging the card forwardly along its central line to enable its edges to be passed back of the overhanging ledges so 45 as to spread out thereunder when the middle portion of the card is moved against the table. Preferably the top of the type-bar segment is used as a lower edge gage to position the card for writing on the upper line 50 thereof, and the usual wing-scales are omitted since, if present, they would interfere with the use of the segment for gaging purposes.

It is also proposed to use the card with a tally-strip device. After the upper line on

the card is typed, the line-space and carriage-return lever is operated and the tally-strip advanced. The card or sheet tends to advance with the tally-strip, but, in case this movement is not completed, the card may be 60 grasped by the operator and positioned by means of the upper edge-gaging means on the aligning table. To avoid interference with the fingers in handling the cards, the aligning table may be provided at its upper 65 edge with a recess of sufficient size to permit insertion of the card to its lower position without interference with the fingers.

Other features and advantages will hereinafter appear. 70

In the accompanying drawings,

Figure 1 is a front view, showing the type-bar segment and the platen-frame of an Underwood standard typewriter with my invention applied to the latter. 75

Figure 2 is a sectional side view, showing the card with its lower edge gaged by the type-bar segment.

Figure 3 is a detail perspective view of 80 one end of the aligning table.

Figure 4 is a sectional side view similar to Figure 2, showing the card with its upper edge gaged at the upper edge of the aligning table.

Figure 5 is a sectional view of the aligning 85 table or chute, showing the manner in which the card is bent in placing it in the chute.

Upon the depression of keys, not shown, type-bars 11 will be swung upwardly and rearwardly to cause types 12 thereon to strike a platen 13 of which the axle 13^a is journaled in the ends 14 of the platen-frame. The proper position of the types at the printing point is obtained by means of a type-bar guide 15 which is secured to the front of a type-bar segment 16 and extends above the horizontal upper surface of the latter. 90

Mounted on the ends 14 of the platen-frame are left and right-hand brackets 17 and 18, respectively, between which extend rods or shafts 19 which pass through slots 20 of brackets or plates 21 mounted on a rod 22, connecting the ends 14 of the platen-frame, and prevent the brackets 21 from turning about said rod 22. 95

Each of the brackets 21 is provided at its front with a lug 23 extending inwardly therefrom, and these lugs serve to support 100 105 110

an aligning table or plate 24 secured to the front of bars 25 secured to said plate and held on the lugs 23 by headed studs 26 passing through slots 26^a in the ends of bars 25 5 and secured to the lugs 23. Secured to the table or plate 24 by any suitable means, such as screws 27 at a suitable distance apart to receive the therebetween a card of the size to be used, are two side-edge guides 28 10 and projecting inwardly from the tops of these guides are ledges or flanges 29. It will be seen that the structure just described constitutes a card-inserting chute.

The ledges 29 are cut away adjacent the 15 upper edge of the table 24 so as to provide openings 30 to permit a card or sheet to be inserted over upper edge gages or lugs 31. The guides 28 and the ledges 29 may be unitary in structure or may be separate and 20 fastened together in any suitable manner, as by means of screws or by brazing. The right-hand guide is also provided with a resilient arm or finger which may be in the form of a spring 32 to engage the platen 13 25 at the printing line.

The rear rod or shaft 19, Figure 2, may serve to support the delivery roll of a tally-strip 33, which, after passing around the platen 13 and a guide 34, is wound upon 30 the upper rod or shaft 19 on which is fixed a ratchet-wheel 35. Upon operation of the usual line-space and carriage-return lever 36, a slide 37 will be moved to the rear, and, by means of a pawl, not shown, will actuate 35 the ratchet 38 fixed on the platen-axle 13^a and actuate the platen. The movement of the slide 37 will cause a link 39 connected thereto to operate an arm 40 and also, by means of a pawl 41 loosely mounted on a 40 pivot 42 connecting the link 39 and the arm 40, to actuate the ratchet-wheel 35 and advance the tally-strip.

The operation is preferably as follows: Each card 43 to be filled out is grasped 45 at the top and bent or bulged forwardly at its middle line from top to bottom, so that the sides will extend to the rear and the lower corners may readily be inserted through the openings 30 and beneath the 50 ledges 29. Such bending diminishes the effective width of the card and facilitates its insertion, while, upon release of the card, it will return to its normal width. The card may be bulged sufficiently to pass its 55 edges between the ledges 29 and then allowed to snap into place on the table 24. After this, the card 43 is moved downwardly until its lower edge engages the flat upper surface of the segment 16. As shown 60 in Figure 2, the card is of such size that, when gaged in this manner, the upper of the two lines to be typed will lie at the printing line. To enable gaging of the lower edges of the cards in this manner, the usual 65 wing-scales are omitted. It should be un-

derstood that other gaging means for the lower edge of the card may be provided.

Entries may then be typed upon the card through a usual ribbon, not shown, and a carbon copy made on the tally-strip 33 by means of a carbon-sheet (not shown), positioned between the card 43 and the tally-strip 33. When the entries on the first line are completed, the lever 36 is actuated to shift the carriage to the right and to line-space the platen and also advance the tally-strip 33. The spring 32 presses the card 43 toward the platen 13, so that, upon line-spacing, there will be a tendency to advance the card 43. In case this movement is insufficient, the final positioning of the card may be insured by grasping it by its upper edge and gaging it against the lugs 31 which constitute upper edge-gaging means. To enable the card 43 to be grasped at the upper edge when in its lower position, the table 24 is provided with a recess 44 at its upper edge, this recess also serving to facilitate the downward movement of the card when originally inserted.

After the typing on the lower line of the card is completed, the card may be grasped at its upper edge and withdrawn from the chute, another card being inserted in the same manner. This operation may be repeated until all of the cards have been filled out.

Variations may be resorted to within the scope of the invention, and portions of the improvements may be used without others.

Having thus described my invention, I claim:

1. In a typewriting machine, in combination, a platen, a sheet-supporting table above said platen, side-edge guides for a work-sheet on said table having projections to overlie the sides of the work-sheet and hold it on the table, and a resilient finger carried by said table and positioned to press said work-sheet against the platen.

2. In a typewriting machine, in combination, a platen, a sheet-supporting table above said platen, side-edge guides for a work-sheet on said table having projections to overlie the sides of the work-sheet and hold it on the table, and means to hold said work-sheet against the platen, comprising a resilient finger extending from one of said side-edge guides to the writing line so as to hold the work-sheet against the platen.

3. In a typewriting machine, in combination, a platen, a platen-frame, type-bars, a type-bar segment, a chute above the platen to guide a work-sheet to the platen at the printing line in a direction to enable the lower edge of the work-sheet to be gaged against the upper edge of said segment to determine one line-space position of the sheet, and resilient means extending from the chute above the work-sheet to press the

latter against the platen at the printing line.

4. In a typewriting machine, in combination, a platen, a platen-frame, type-bars, a type-bar segment, and a chute above the platen to guide a work-sheet to the platen at the printing line in a direction to enable the lower edge of the work-sheet to be gaged against the upper edge of said segment to determine one line-space position of the sheet, said chute being cut away at its upper part to enable the operator, in inserting the work-sheet, to maintain his grasp on the upper edge thereof until the sheet is positioned by the segment.

15 5. In a typewriting machine, in combination, a platen, a platen-frame, type-bars, a type-bar segment, a chute above the platen to guide a work-sheet to the platen at the printing line in a direction to enable the lower edge of the work-sheet to be gaged against the upper edge of said segment to determine one line-space position of the sheet, a tally-strip device to feed a tally-strip around the platen, means to line-space said platen, connections between said line-space means and said tally-strip device whereby the latter may be actuated by the former, and resilient means mounted on said chute and engaging the platen at the printing line to hold the sheet against the platen to be line-spaced thereby.

6. In a typewriting machine, in combination, a platen, a platen-frame, a stationary chute on said frame to guide a work-sheet to the platen, said chute comprising a supporting element and sides spaced apart sufficiently to receive the work-sheet, said sides having overhanging portions to hold the work-sheet in position on the supporting element, stationary means adjacent the upper ends of said overhanging portions to gage the upper edge of said work-sheet to determine a writing-line position thereof in the chute, and means carried by said chute to press said work-sheet against the platen at the printing line, to cause the work-sheet to be fed, by engagement with the platen, to the writing position determined by the upper-edge-gaging means.

50 7. In a typewriting machine, in combination, a platen, a sheet-supporting table above the platen, side guides for a work-sheet on said table to guide it to writing position and to feed it in letter-feed and return directions, and means for clamping the work-sheet to hold it stationary in writing posi-

tion, said means being arranged to occupy its effective position at all times and being constructed to yield to permit the work-sheet to be forced beneath it in its effective position.

8. In a typewriting machine, in combination, a platen, a sheet-supporting table above the platen, means carried by the table to press a work-sheet supported on the table against the platen, said means being sufficiently yielding to permit the work-sheet to be inserted beneath it when in its effective position and therefore constructed to feed the work-sheet yieldingly in co-operation with the platen, and gages in the path of the work-sheet to intercept its upper edge as it is fed yieldingly by the platen to arrest the work-sheet in a predetermined writing-line position.

9. In a typewriting machine for writing upon a succession of forms, each designed to receive two lines of writing only, in predetermined locations, in combination, a platen, a paper-table above the platen, side members for engaging the side edges of a form, to feed it from side to side with the platen, a clamp arranged to be always in its effective position and sufficiently yielding to permit the insertion of the form beneath it in its effective position, a lower-edge gage for determining the first writing-line position of the form, and a leading-edge gage to intercept the form to arrest it in its second writing-line position when it is fed by the platen in cooperation with the yielding clamp.

10. In a typewriting machine for writing upon a succession of form cards, each designed to receive two lines of writing only, in predetermined locations separated by a line-space interval, in combination, a platen, means to hold a card against the platen, and means for locating the card in two positions, including a stationary lower edge gage to intercept the lower edge of a front inserted card to locate the card in its first writing-line position, and a stationary upper edge gage located to intercept the card as it is fed forward from its first writing-line position to arrest it in its second writing-line position at a line-space distance from the first writing-line position.

JAMES C. ANDERSON.
